UNITED STATES PATENT OFFICE.

WILLIAM D. ELLIOT, OF BIGTIMBER, MONTANA.

PAPER-BAG HOLDER.

1,328,950.

Specification of Letters Patent. Patented Jan. 27, 1920.

Application filed July 30, 1919; Serial No. 314,186.

To all whom it may concern:

Be it known that I, WILLIAM D. ELLIOT, a citizen of the United States, residing at Bigtimber, in the county of Sweet Grass 5 and State of Montana, have invented certain new and useful Improvements in Paper-Bag Holders, of which the following is a specification.

This invention relates to certain improvements on the device for which Letters Patent of the United States were granted me July 23, 1918, Number 1,273,341 and has for its object mainly to simplify the operating means, whereby the bag holding devices 15 are released when it is required to supply a new pile of bags to replace those which have been used.

The invention also relates to improvements in the general structure tending to 20 reduce the number of parts and render the operating elements more positive and certain in operation.

The drawings illustrate a preferred embodiment of the invention. However, it is 25 to be understood that in adapting the same to meet different conditions, various changes in the form, proportion, and minor details of construction may be resorted to without departing from the nature of the invention 30 as claimed hereinafter.

Referring to the accompanying drawings:

Figure 1 is a view in elevation of the improved paper bag holder, the intermediate portion being broken away; and

Fig. 2 is a side view of the upper portion of the device.

Corresponding and like parts are referred to in the following description and indicated in both views of the drawings by like 40 reference characters.

The stand and coöperating parts are substantially the same as corresponding parts in my previous patent herein noted. The stand comprises four uprights or standards 45 2 which are connected at their upper and lower ends, said uprights converging toward their upper ends and having slots 9 in which are mounted transverse rods 8 which constitute the bag holders. A plate 1 connects the lower ends of the uprights and constitutes the base which is extended and provided with feet. A plate 3 connects the upper ends of the uprights or standards. Contractile helical springs 17 connect the 50 several rods 8 with the shelves 4, which are located at different elevations in the length

of the stand. The springs 17 normally exert a downward pull upon the rods 8, so as to press the same upon the paper bags supported upon the shelves 4 and extensions 28 60 thereof. A contractile spring 16 passes beneath guide rollers 20, mounted upon the base 1 and has its ends connected to the lowermost rods 8.

Slides 13 are mounted upon the stand so 65 as to receive a limited vertical movement. It is to be understood that a slide 13 is provided for each upright or standard. The slides upon the side of the stand having the shelf extensions 28 are connected for simultaneous movement to admit of a corresponding movement being imparted to the rods or bag holders 8, whereby they may be elevated to admit of the shelves being replenished or supplied with a pile of bags of 70 proper size. Hooks 12 are pivotally mounted upon the slides 13 and are adapted to make detachable connection with the respective rods or bag holders. A metal strap 23 is attached to the upper end of each slide 13 75 and is formed with a longitudinal slot 24 to receive a projection 25 at the end of a lever 29. There are a pair of levers 29 which are secured intermediate of their ends to a crosspiece 26, which is mounted in a 80 bracket 31 secured centrally to the upper portion of the stand. The crosspiece 26 is provided with a handle 27. The levers 29 have projections 25 at both ends which enter the slots 24 of the metal strap 23. When the 85 handle 27 is in vertical position the levers 29 are disposed horizontally and their projections 25 occupy a position at the upper ends of the slots 24. Movement of the handle 27 to one side or the other effects a 90 turning of the levers 29, whereby one of their ends is elevated and the opposite end lowered. The ends of the levers 29 moving upward elevate the slides 13 connected therewith and lift the rods or bag holders 100 8, thereby admitting of a pile of bags being placed upon the shelves beneath the rods or holders 8. It is to be understood that the hooks 12 are engaged with the rods or bag 105 holders 8. After the shelves have been properly supplied with the paper bags, the slides are returned to normal position and the rods or holders 8 engaging the bags clamp the same, whereby the hooks 12 automatically disengage themselves from the respective rods or bag holders. To supply the 110 shelves on the opposite side of the stand, the

handle 27 is moved in a reverse direction to that previously described, with the result that the rods or bag holders 8 on the side of the stand to be supplied with bags are 5 lifted, thereby admitting of the bag being placed in position upon the shelves, after which the slides 13 are returned to normal position. The hooks 12 are adapted to detachably engage the rods or bag holders, as 10 will be readily understood. The straps 23 are in the nature of links and are pivotally connected at their lower ends to the slides 13, thereby preventing any binding of the projections 25 in the slots 24.

15 The foregoing description and the drawings have reference to what may be considered the preferred, or approved form of my invention. It is to be understood that I may make such changes in construction and 20 arrangement and combination of parts, materials, dimensions, et cetera, as may prove expedient and fall within the scope of the appended claims.

Having thus fully described my invention, what I claim as new and desire to secure by Letters Patent is:—

1. A paper bag holder, comprising a stand including a plurality of shelves for receiving the bags, a holder coöperating 30 with each of the shelves to retain the bag in position thereon, a slide common to all of the holders upon the same side of the stand, a lever mounted upon the stand, a handle for operating the lever and a slotted link 35 connection between the lever and slide.

2. A holder of the character specified, comprising a stand including a plurality of shelves, a holder coöperating with each of the shelves, means for connecting the 40 holders to effect simultaneous movement thereof, a lever mounted upon the stand and a link between the lever and connecting means for the holders and having a pin and slot connection with one of the parts.

3. In a device of the character specified, 45 a stand including a plurality of shelves disposed to support articles at opposite sides of the stand, holders at opposite sides of the stand, one for each of the shelves, slides at opposite sides of the stand, and adapted 50 to coöperate with the respective holders, a lever mounted centrally upon the stand and means connecting opposite ends of the lever with the respective slides, whereby the slides at one side of the stand may be operated 55 to lift the holders associated therewith while the slides at the opposite side remain inactive.

4. A holder of the character specified, comprising a stand having a plurality of 60 shelves disposed for supporting articles at opposite sides of the stand, holders for the respective shelves for retaining the articles in position thereon, a pair of slides at each side of the stand, means for detachably connecting 65 the slides with the holders, a lever mounted centrally upon the stand and links forming connecting means between the ends of the lever and the respective slides and having a pin and slot connection with one of 70 the parts.

5. A holder of the character specified, comprising a stand provided with a plurality of shelves, a holder for each of the shelves, oppositely disposed slides, means on 75 the slides for detachably engaging the holders, levers mounted centrally upon the stand and links connecting opposite ends of the levers with the respective slides and having a pin and slot connection with one 80 of the parts.

In testimony whereof I affix my signature in presence of two witnesses.

WILLIAM D. ELLIOT.
